(57) **CLAIM**

The ornamental design for a device for storing papers or the like, as shown and described.

DESCRIPTION

FIG. 1 is a front perspective view of a binder of the design;

FIG. 2 is a top view thereof; and,

FIG. 3 is a top view of the binder with the binder opened and laid flat.

The evenly spaced broken lines showing portions of the device for storing papers or the like are for the purpose of illustrating environment and form no part of the claimed design. The long and short broken lines which define the bounds of the claimed design form no part thereof.

1 Claim, 3 Drawing SheetsFIG. 1

FIG. 2

FIG. 3
